UNITED STATES PATENT OFFICE.

JAMES POPHAM, OF MONTREAL, QUEBEC, CANADA.

SEAM FOR BOOTS AND SHOES.

SPECIFICATION forming part of Letters Patent No. 230,654, dated August 3, 1880.

Application filed May 28, 1880. (No model.) Patented in Canada January 10, 1880.

To all whom it may concern:

Be it known that I, JAMES POPHAM, of the city of Montreal, in the district of Montreal and Province of Quebec, Canada, have invented 5 certain new and useful Improvements in the Seams of Boots and Shoes; and I do hereby declare that the following is a full, clear, and exact description of the same.

My invention is applicable to all boots and 10 shoes made of leather, of every description and all sizes, whether men's, women's, misses', children's, boys', or youths', but will be found specially useful in cases in which extra strength of construction is required and the boot or 15 shoe is exposed to more than the ordinary wear and tear and to dampness. It may be briefly described as consisting in securing together the edges of the several pieces going to make up the uppers of boots and shoes— 20 *i. e.*, making the seams—by means of rubber cement placed between their overlapping surfaces and a continuous line of rivets passing through both pieces.

In the drawings hereto annexed, and forming 25 part of this specification, Figure 1 is a view of a seam made according to my invention; Fig. 2, a section through same, and Fig. 3 a view of a boot embodying my invention.

Similar letters of reference indicate like 30 parts.

My improved water-proof seam is constructed by first placing between the pieces of leather to be joined (marked A and B in the drawings) a close layer of rubber cement sufficient to 35 keep out water but not to join the pieces securely together. I then run a line or lines of stitching, as shown at *dd*, through the pieces which overlap each other, after which I drive through both thicknesses rivets C, at short 40 distances apart, in a continuous line throughout the seam. From this it will be understood that the rubber cement obviates all

chance of wet oozing through the seam. The stitching prevents the edges of the leather from turning up, besides making the seam 45 more compact, and the continuous line of rivets strengthens the joint and has the effect of making the seam absolutely indestructible.

The rivets used may be of any metal of which they are usually formed; but, in boots of a su- 50 perior class, of copper or other substance not affected by wet. In all cases they will be inserted so as not to strike out the pieces embraced in them, which might weaken the leather and make the boots liable to leak, my 55 invention being specially intended to overcome this difficulty.

It will be seen that by this invention a seam is formed at very little cost, at the same time being water-tight and of great strength and 60 durability, and that consequently boots made in this way will be found specially serviceable for men employed in lumbering, for fishermen, and railway navvies, as from their non-liability to rip in comparison with other boots they 65 will not need repairs.

I am aware that rivets placed in a continuous line have been used to join together the uppers of moccasins, and also that cement has been used for a like purpose, and therefore 70 claim neither of these, broadly.

What I claim is as follows:

As an improved article of manufacture, a boot or shoe having the several pieces forming the upper joined together by a continuous 75 line of rivets and stitching, and having rubber cement placed between their meeting surfaces, whereby I obtain not only water-proof seams, but also a permanent union of parts, all as herein set forth.

JAMES POPHAM.
